TEETERING DEVICE

Elmer H. Loker, Sioux City, Iowa, assignor of one-half to Edward P. Stahly, Sioux City, Iowa

Application July 23, 1945, Serial No. 606,607

3 Claims. (Cl. 272—54)

1

My invention relates to a teetering device.

An object of my invention is to provide a teetering arrangement wherein the teetering effect is obtained by the manipulation of the hands with certain members in connection with the usual manner of operation.

A further object of my invention is to provide an arrangement whereby the teetering effect can be caused as desired, by one person only.

A further object of my invention is to provide an arrangement wherein the teetering effect is provided by means of the feet in conjunction with the hands, etc.

A further object of my invention is to provide a well balanced arrangement which is easily operable by children, is simple to manufacture, and can be manufactured at a reasonable cost.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side sectional elevation of the device and taken substantially along the lines 1—1 of Figure 2.

Figure 2 is a plan view of Figure 1.

Figure 3 is a side sectional elevation of a modified form of the arrangement.

Figure 4 is an end detail of the base of the arrangement shown in Figures 1 to 3 inclusive.

Figure 5 is a further modification, and

Figure 6 is a plan sectional view taken along the lines 6—6 of Figure 5.

I have used the character 10 to designate a pair of spaced base members to which are attached the rubber bosses 11 for resting the arrangement upon the floor, and attached at 12 to the members 10 are the upwardly converging supports 13 which terminate at the apexes 14. Attached to the portions 14 are spacers 15. The teeter board itself is indicated by the character 16 and is preferably made up of a flat piece with its width being positioned vertically as shown, the member 16 being attached at 17 to the two seats 18. Attached at 19 to the member 16 and at either side thereof, are the downwardly converging pieces 20 which are attached together at 21, a further piece 22 being attached therebetween as a filler member.

Passing through the portions 14, 15, 22, and the member 16 is a substantially strong pin 23, upon which pin the member 16 rocks.

Pivots attached by means of suitable pins 55 a pair of upwardly converging braces 44 are

5 at 24 are the lengthened links 25 which are pivotally attached at 26 between the pairs of vertical arms 27, which arms 27 straddle the member 16. The arms 27 are pivoted on the lower shafts 28 which pass through the base members 10 and include suitable spacers 29 attached thereto (see Figure 4). The members 27 are further braced at 30 and are attached at 31 to the handles 32, and attached at 33 across the members 27 are the foot receiving bars 34.

10 It will now be seen that children seated upon the seats 18, when grasping the handles 32 and forcing them backwardly and forwardly in the direction of the arrows 35 will cause the arms 15 27 to pivot at 28, at the same time causing the links 25 to rock the members 20 through the pivot connections at 24. Since the members 20 are securely attached to the member 16, this will cause this member 16 to rock back and forth in the direction of the arrows 36 thereby providing 20 a rocking action by the use of the hands. In this manner, one child only can operate the arrangement, since the use of the hands on the handles 32 will maintain the rockable portions of the device at any inclined position. This 25 manual operation also is amusing, balances the working parts, and makes the teetering action much easier. The children can rest their feet on the cross-bar 34, and by pushing on the same 30 inwardly will assist in the above described action.

Figure 3 illustrates a modified form of the arrangement wherein most of the above described parts are used, these parts being designated by the same characters. This arrangement, however includes a few slight changes, and includes 35 two pairs of vertical links 37 which straddle the member 16, and which are pivoted at 38 thereto. Pivoted at 39 between the members 37 are the lever members 40 which are pivoted at 41 between the members 27, the levers 40 extending outwardly and being attached at 42 to the foot bearing transverse bars 43. In this structure, the above 40 described links 25 will be received between the members 37.

45 By manipulating the handles 32, the member 16 will rock in accordance with the action as described hereinabove, and by pressing downwardly on the foot bars 43 the leverages exerted through the members 40 will cause the links 37 to 50 assist in the rocking action through the pivotal engagement at 38.

Figures 5 and 6 illustrate a further modified form of the arrangement in which the member 16 and the seats 18 are the same, and wherein 55 a pair of upwardly converging braces 44 are

attached together at 45, the braces 44 being attached at 46 to each side of the single base member 47, there being thus provided two pairs of braces or supports 44. The member 16 is pivotally attached at 48 to these braces. Attached to the central member 47 are a pair of transverse end members 49 to stabilize the structure.

Pivotally attached at 50 between the members 44 are the two links 51 which are pivotally attached at 52 to the upwardly extending arms 53 which are pivotally attached at 54 to the member 16, which arms 53 straddle the member 16. Also pivotally attached at 55 to the upper extremities of the arms 53 is the horizontal member 56 which terminates in the handles 57 attached thereto.

It will now be seen in this latter structure, that children seated upon the seats 18 can push forwardly and pull rearwardly on the handles 57, whereby the linkages above described will correspondingly through the pivotal engagement at 54, etc., cause the beam 16 to rock upon the pivot 48. It will be noted that the members 51 and 53 are at an angle to each other substantially less than a right angle in order to provide the necessary folding action to cause the member 16 to rock.

It will not be seen that I have provided all of the advantages mentioned in the objects of my invention with further advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A teetering device comprising a support, a teetering member pivoted centrally on said support, vertical arms pivoted to the support, handles attached to said arms for graspment by person seated at the ends of said teetering member, said arms being attached to said teetering member 45.

so that movement of said handles will rock the same, including links pivotally attached to the arms, brackets attached to said teetering member, said links being pivotally attached to said brackets.

2. A teetering device comprising a support, a teetering member pivoted centrally on said support, vertical arms pivoted to the support, handles attached to said arms for graspment by person seated at the ends of said teetering member, said arms being attached to said teetering member so that movement of said handles will rock the same, including links pivotally attached to the arms, brackets attached to said teetering member, said links being pivotally attached to said brackets, foot receiving members attached to said arms.

3. A teetering device comprising a support, a teetering member pivoted centrally on said support, vertical arms pivoted to the support, handles attached to said arms for graspment by person seated at the ends of said teetering member, said arms being attached to said teetering member so that movement of said handles will rock the same, including links pivotally attached to the arms, brackets attached to said teetering member, said links being pivotally attached to said brackets, further links pivotally attached to said teetering member, levers pivotally attached to said further links and to said arms, foot receiving bars attached at the outer extremities of said levers, whereby foot action against said foot receiving members will cause further rocking action of said teetering member.
